STEPHEN D. LAYMAN, OF NEWARK, NEW JERSEY.

HINGED LAST.

1,144,364.

Specification of Letters Patent. Patented June 29, 1915.

Continuation of application Serial No. 878,206, filed December 21, 1914. This application filed January 18, 1915. Serial No. 2,823.

To all whom it may concern:

Be it known that I, STEPHEN D. LAYMAN, a citizen of the United States, and a resident of Newark, county of Essex, and State of 5 New Jersey, have invented certain new and useful Improvements in Hinged Lasts, of which the following is a specification.

My invention relates to hinged lasts for use in the manufacture of shoes and other 10 footwear, and relates more particularly to the improvement of hinged connections between the parts of such lasts in important respects.

The present application is a continuation 15 of my former application, Serial No. 878,206, filed Dec. 21, 1914, for hinged lasts, and among the objects of the present invention is to provide means for facilitating the assembly of hinged connecting means as described in my said former application, and the provision of means for imparting additional rigidity to lasts equipped with hinged connecting means constructed in accordance with my said former application.

25 Other objects of my invention will appear in connection with its further description, and with the foregoing and related objects in view, my invention consists in the parts, improvements and combinations herein set 30 forth and claimed.

In the accompanying drawing forming a part of this specification, and wherein the same reference numerals are uniformly applied to designate the same parts throughout, Figure 1 is a side view of a last embodying the present invention. Fig. 2 is a cross-sectional view thereof taken on the line 2—2, Fig. 1. Figs. 3 and 4 are side views, respectively, of the connecting disks, 35 and Fig. 5 is a fragmentary cross-sectional view similar to a portion of Fig. 2, but showing a slightly modified construction.

40 Reference numeral 10 represents the toe or forward part of the last and 11 designates the heel or rear part thereof. The rear lower part 12 of the portion 10 of the last and the forward part 13 of the portion 10 of the last normally abut against one another, as shown in Fig. 1, and the upper parts 45 thereof are cut away to about the center of rotation, preferably upon a bevel, as indicated at 14 and 15, respectively, to make room for the turning of the two parts of the last relative to one another. The provision 50 made for receiving the rotary connecting

means comprises a transverse bore 16 extending transversely through the last at the center of rotation of the two parts 10 and 11 and formed part in each thereof, and a longitudinally extending recess made up of 60 the partial recesses 17 and 18 also formed in the parts 10 and 11 of the last respectively. The disks 19 and 20 are received within the recesses 17 and 18 and preferably fit fairly close therein, as shown in Fig. 2. 65 These disks are arranged side by side as shown in Fig. 2, and so arranged are received within the recesses 17 and 18 in the two parts of the last.

In the form shown the disk 19 is secured 70 to the forward portion 10 of the last to turn therewith, being provided with two holes 21 and 22 through which the pins 23 and 24 are passed, which pins also pass through the openings 25 and 26 provided 75 in the portion 10 of the last for the reception thereof, and the disk 19 is thereby rigidly held in the part 10 of the last and so that it can have no turning movement in relation thereto. The pins 23 and 24 also 80 pass respectively through the slots 27 and 28 in the disk 20, said slots being of substantially the same length and being formed concentrically with respect to the circular periphery of the disk. While such 85 disks are preferably circular in general outline, this particular form is not essential, so long as the holes and slots are concentrically arranged. With the arrangement so described it will be apparent that 90 whereas the disk 19 is fixed with respect to the member 10 of the last, the disk 20 can rotate with respect thereto throughout the extent defined by the slots 27 and 28. On the opposite sides of the disks 19 and 20 95 the reverse relation is had, the disk 20 being provided with holes 29 and 30 through which pass pins extending transversely through openings 31 and 32 provided therefor in the rear member 11, such pins also 100 passing through the slots 33 and 34 in the disk 19. The disk 20 is thus fixed so that it is prevented from rotating with respect to the member 11, whereas the disk 19 and the member 10 secured thereto may rotate 105 with respect to the portion 11 of the last, the disk 19 rotating with respect to the member 11 to the extent defined by the concentric slots 33 and 34 in the disk 19. The concentric slots 27, 28, 33 and 34 being all 110

of substantially the same extent, and the holes 21, 22, 29 and 30 being placed an equal distance from the center of rotation, it will be seen that by this construction a 5 rotatable connecting means is provided between the parts 10 and 11 of the last, and that such connecting means extends over a considerable surface, and the four pins which secure the connecting means to the 10 last members being arranged in a circle, the entire connecting means turns thereon as upon a pivot of very large diameter.

Any convenient arrangement of spring means for normally holding the portions 10 and 11 of the last so that the parts 12 and 15 13 abut may be used. In the form shown the member 20 secured to the rear portion 11 of the last is provided with an upstanding part 35 having a forwardly projecting lug 20 36 which is received within the opening in the coil spring 37, said spring 37 entering a recess 38 provided therefor in the forward last member 10. Other constructions serving the same purpose may be made use of if 25 desired, certain alternative forms of construction for this and related purposes being shown and described in my said former application Serial No. 878,206, any one of which or others may be made use of in connection with the device of the present application.

When the disks 19 and 20 are separated and no means of preliminary connection therebetween is provided, as was the case in 30 my said prior application, more or less difficulty is encountered in assembling the same and in securing the pins, which secure the same, in the holes 25, 26, 31 and 32 and the parts 10 and 11 of the last respectively.

40 A structure in accordance with the present invention obviates all difficulties of this sort and at the same time serves to give the last added rigidity in a side to side direction. As such preliminary assembling 45 arrangements are preferably to remain permanently in the hinged structure when the same is put into a last, I preferably pass the same through the centers of the disks 19 and 20, as at this point there is no relative 50 movement except the movement of rotation upon a common center. To this end the disks 19 and 20 are provided with central holes 39 and 40 and a pin 41 is passed therethrough and means are provided on such 55 pin for holding the disks 19 and 20 together and preferably fitting fairly closely within the transverse bore 16 so as to give additional side to side rigidity. Such result may be secured by the provision of sleeves 60 42, 42, one on the pin 41 on each side of the disks 19 and 20, which pin may be headed over, as at 43, 43, or other constructions may be resorted to for obtaining a similar result as, for example, a pin 44 may be provided having an integral enlargement 45 on

one end thereof and a sleeve 46 on the opposite end, the pin being headed over beyond the sleeve 46, as shown at 47, Fig. 5. Other forms of constructions may be resorted to for this purpose so long as the same pass 70 centrally through the disks 19 and 20 and fit fairly closely within the transverse bore 16.

It will be seen that with a device constructed as above set forth the assembly of 75 the parts is considerably facilitated and at the same time a more rigid and substantial structure may be secured. Furthermore, while the center of rotation is definitely defined by the disk, pin, slot and hole construction at points away from the center of rotation, the provision of the pin passing through the central openings in the disk serves to a slight extent at least in securing 80 a smooth and even pivoting action between 85 the disks and the parts of the last to which they are secured. While the pin preferably fits fairly closely within the openings 39 and 40 in the disks, this is not essential as 90 an extended pivotal mounting is provided for the disks on the pins which secure the disks to the last portions, and the fit of the pin in the holes 39 and 40 may be extremely loose so far as the pivoting action is concerned. The side to side rigidity of the 95 whole structure is, of course, improved by giving the pin 41 or 44 a fairly close fit in the openings 39 and 40.

It is to be understood that the construction 100 illustrated is only for the purpose of affording a clear disclosure of my invention and making it readily understood, and that the invention is not limited to such specific construction except as set out in my claims, and that various modifications in and departures 105 from such precise construction may be made, within the scope of my claims, and without departing from my invention or sacrificing any of its advantages.

Having thus described my invention, I 110 claim:

1. In a last, heel and toe portions, a pair of disks set side by side therein, means for securing one of said disks rigidly to one of the last portions and rotatively to the other of said last portions, means for securing the other disk rigidly to the first named last portion and rotatively to the other of said last portions, and means for rotatively connecting the disks at substantially the centers 115 thereof, substantially as set forth.

2. In a last, heel and toe portions having a longitudinally extending recess and an intersecting transversely extending recess, each of said recesses formed part in each of 120 said last portions, a pair of disks in said longitudinally extending recess, means for attaching one of said disks rigidly and the other rotatively to one of said last portions, means for attaching the other of said disks 125 130

rotatively to said first named last portion and rotatively to the other last portion, and means arranged within the transversely extending recess for rotatively securing the 5 two said disks together, substantially as set forth.

3. In a last, heel and toe portions having a longitudinally extending recess formed part in each thereof and a transverse recess 10 also formed part in each thereof and intersecting the first named recess, a pair of disks in said longitudinal recess, each of said disks being provided with holes and concentric slots, the holes in one being opposite 15 site the slots in the other, pins in said last portions and extending through said holes and slots, and means received in said transversely extending recess for rotatively connecting the two disks together, substantially 20 as set forth.

4. In a last, heel and toe portions having a longitudinally extending recess formed part in each thereof and a transversely extending bore intersecting said longitudinal 25 recess and also formed part in each of said last portions, a pair of disks, each of said disks being provided with holes and slots, the holes in one being opposite the slots in the other, pins in said last portions and extending through said holes and slots, said 30 disks being each provided with an aperture at substantially its center, a pin extending through said aperture, and means on said

pin on each side of said disks for holding said disks together and fitting substantially 35 closely in said transverse bore, substantially as set forth.

5. In a last, heel and toe portions, a pair of disks set side by side therein, means for securing one of said disks rigidly and the 40 other rotatively to one of said last portions, means for securing the other of said disks rotatively to the first named last portion and rigidly to the other last portion, and means extending transversely through the 45 last and through said disks for rotatively connecting said disks together and for affording additional rigidity to the construction, substantially as set forth.

6. A last divided transversely into two 50 portions, a first connecting means fixed in one portion and rotatively connected directly to the other portion, a second connecting means fixed in the second portion and rotatively connected directly to the first 55 portion, and means for rotatively connecting said first and second connecting means to one another, substantially as set forth.

In testimony that I claim the foregoing, I hereto set my hand, this 16th day of January, 1915.

STEPHEN D. LAYMAN.
